TYPE BAR FOR TYPEWRITERS AND THE
LIKESeyed Khalil, New York, N. Y., assignor to Royal
Typewriter Company, Inc., New York, N. Y., a
corporation of New York

Application January 21, 1936, Serial No. 60,025

13 Claims. (Cl. 197—27)

This invention relates to improvements in type bars for typewriters and the like, comprising a series of links, one of which carries the type and the others cooperating therewith in the accomplishment of the result, thereby providing a new and novel typebar performance.

One object of the invention is the provision of a type carrying element of comparatively short length, normally spaced apart from the platen 10 a distance greater than its length, and having associated therewith a plurality of links, which during a printing operation, is initially brought to a position near the platen with the links in substantially constant relation to each other; 15 after which, as the type advances to printing position, the relation of the links to each other is progressively changed and the movement of at least one of the links is reversed; thereby a suitable distance is provided between the type elements and the platen, and the momentum of 20 the same is reduced, thereby reducing the noise produced by the type as it contacts the platen.

Another object of the invention is the provision of a typewriter including linkages between the key and the type carrier through which the 25 force applied to the key is delivered to the type in increased ratio from a position of the type adjacent to the platen up to the printing position; whereby clear characters may be obtained and a large number of copies may be produced.

A further object of the invention is the provision in a typewriter of a type carrying member, a compound linkage, and a plurality of pivots connecting the member to the linkage, the latter 30 being so arranged that as it is moved the pivotal movement of the member is about a point varying in position along a line between at least two of the pivots, thereby bringing one edge of the type into printing contact with the platen, and successively bringing the remainder of the face 35 of the type into contact, with a rolling motion, and producing a neat, clean-cut impression.

Still another object of the invention is the provision in a "noiseless" typewriter of linkages 40 between the keys and the type carriers including pivotal junctions which form close working fits; thereby preventing vibration, both horizontally and vertically, and eliminating misalignment and misplacement of the printed character.

A further object of the invention is the provision in a "noiseless" typewriter of a plurality of type carriers normally positioned side by side in arcuately-arrayed order of a radius of such 45 length that the side members make comparatively obtuse angles with the plane of the platen

when in the printing position. This overcomes serious difficulties which are present in some machines of the prior art in which the type members are in arcuately arrayed order of a short radius and wherein the side members make acute 5 or critical angles with the plane of the platen.

Another object of the invention is the provision of a "noiseless" movement, the physical dimensions of which are such that it may be mounted in the frames of existing ordinary type- 10 writers.

Still another object of the invention is the provision of new and novel linkages between the keys and the type carriers, adapted to deliver the power from a key to its type carrier in increased ratio, whereby the operator, in accordance with his or her previous training, in actuating the keys, may obtain consistent results at 15 any rate of speed.

A further object of the invention is the provision of a type member, a key for actuating the same and linkages therebetween adapted to impart a rolling motion to the type and increasing pressure from a point adjacent to the platen up to the point of printing contact whereby neither 20 the paper nor the carbon paper is harmed.

Other objects and advantages of the invention will hereinafter appear.

Generally speaking, the mechanical construction of typewriters requires a suitable space between the normal position of the typebars and the platen thereof. The spacing apart of the typebars from the platen is determined by several factors:

First. Many typewriters have forty two typebars, the total thickness of the arcuate array of which prevents the positioning of such typebars beyond a certain distance apart from the platen.

Second. The undesirable angularity of the typebars toward the extreme ends will become 40 more acute by reducing the space between the typebars and the platen.

Third. As the space between the typebars and the platen is reduced, the printing energy which is, in some cases, accumulated by the acceleration of such typebars as they travel from the normal position to the printing position, is proportionately reduced.

Fourth. The greater the space between the typebars and the platen, the louder will be the 45 noise produced when such typebars strike the platen.

In the new and improved "action" herein shown and described, four desirable features are 50 present:

First. The type carriers may be spaced a suitable distance apart from the platen so as to provide ample room therebetween to accommodate the width of the arcuate array without having the type carriers on each end make critical angles when they contact the platen.

Second. Despite the comparatively large distance between the type carriers and the platen, the printing contact between the typebars and the platen is practically silent because, as it will be described in detail in the following specification, the bar bearing the type hereinafter termed "type carrier" is of comparatively short length.

Third. Despite the practically silent contact with the platen, the typebars through new and novel linkages press strongly against the platen so as to produce a plurality of clear copies which is a necessity in many cases.

Fourth. The actual contact between the typebars and the platen is "rolling" due to the fact that the bottom of the type face contacts the platen first after which the remainder of the face successively contacts the platen, and due to the increase, through the linkages, of the power or pressure applied to the key thereof, controlled printing is provided, one of the characteristics of which is good alignment and accurate interspacing.

The main advantages of the new and improved action in commercial use are its noiseless feature, its printing power and the neat clean-cut impressions.

While this action is not absolutely silent, the term "noiseless" is merely comparative and the noise produced by this action is very little as compared to that produced by existing typewriters.

The term "printing power" may be taken to mean the power applied to the key which is stepped up in increasing ratio through the linkages immediately before and as the type comes in contact with the platen.

Due to this printing power a neat impression of the type is obtained on a larger number of copies. Further, the clarity of the printing is materially improved, a feature which has been desirable but unobtainable heretofore.

The surface of all paper has undulations which, in the ordinary typewriter, have to be hammered down to the surface of the platen before it receives the impression of the type. Contrasted with this, the rolling action produced in the new and improved typewriter action "irons" out any undulation while and as it prints.

Due to this special feature, the results obtained more closely resemble results obtained from an offset printing machine than the results produced by any existing typewriter.

In the accompanying drawings:

Figure 1 is a side elevation of the new and improved type action in its normal position, at rest;

Figure 2 is a view of the action shown in Figure 1 with the type in an intermediate position;

Figure 3 is an elevation similar to Figure 1 and Figure 2 except that the type has advanced to the printing position;

Figure 4 is a diagrammatic sketch showing a plurality of positions of the type from the normal, at rest, position to the printing position and the positions the linkages assume for the corresponding type positions;

Figure 5 is a cross-sectional view of one of the pivots forming the junction of two of the

links, said view being taken along the line 5--5, Figure 3;

Figure 6 is an enlarged diagrammatic view showing the action of the type as it comes in contact with the paper and showing the rolling action of the type while printing; and

Figure 7 is an elevation of a modification of the action shown in Figure 1.

Referring to Figure 1, a key lever 10 is mounted on a stationary fulcrum 11 and is provided with a key 12. A spring 13 having one end connected to the lever 10 and the other end to a stationary member 14, normally holds the key lever against the stop 15. This stop may be provided with a rubber cushion 16 against which the lever 10 may strike when the key 12 is released.

A second cushion 17 may be provided on the key lever 10 thereby permitting both the cushion 17 and the cushion 16 to come in contact with each other when the key lever is released.

A lever 18, having one end thereof mounted on a stationary fulcrum 19, is preferably angular in form and has its other end connected to one end of a type carrying member 20 by means of a pivot joint generally designated by the numeral 21. The pivot 21 is shown more in detail in Figure 5, and all of the other pivot joints hereinafter referred to have the same general structure.

The pivot joint 21 consists of a stud 22 shouldered on each end and passing through holes in the lever 18 and the member 20. A spacing washer 23 may be positioned between the members 18 and 20 for clearance purposes and in actual practice it has been found that the length of the member 22 from shoulder to shoulder is approximately 2/1000ths greater than the thickness of the lever 18, the washer 23 and the member 20.

A washer 24 is applied on top of the member 20 and a washer 25 is applied beneath the lever 18 after which the ends of the stud 22 are riveted. This gives a very rigid structure with substantially no lost motion and at the same time the members 18 and 20 are free to move.

The type carrying member 20 is also preferably angular in shape and carries at one extremity type members 26 and 27.

The member 20 is connected to one end of a lever 28 by means of a pivot joint 31 which is identical in construction with the pivot 21. The other end of the lever 28 is connected to one arm 29 of a bell crank 30 by means of a pivot joint 38. The mid-point of the bell crank is connected to the lever 18 by means of a pivot joint 39. The arm 31 of the bell crank 30 is connected to one end of a lever 32 by means of a pivot joint 40. The lever 32 is mounted on a stationary fulcrum 33 and its other end is connected to one end of a pull bar 34 by means of a pivot joint 41.

The other end of the pull bar is connected to the key lever 10 by means of a pivot joint 42. The platen 35 is positioned in spaced relation to the type member 26 so that when the type is in printing position, the horizontal center line through the platen coincides with the horizontal center line of the type, as shown in Figure 3 and indicated by the numeral 36.

Figure 1 shows the new action in its normal or at rest position; Figure 2 shows the action with the type carrier 20 in an intermediate position which might be termed a "dead center" position. When the type carrier 20 is in this position, the lever 18 has made its extreme move-

ment to the right, as viewed in the figures, and at the same time the lever 32 and the arm 31 are almost in line with each other.

As the type carrier 20 continues its movement toward the platen, it follows a curved path due to the combined effect of the movement of the pivot 37 in a clockwise direction through the movement of the lever 28, and due to the counter-clockwise direction of the movement of the pivot 21 caused by the movement of the lever 18 to the left.

In other words, the lever 18, up to the "dead center" position, moves to the right and thereafter reverses and moves to the left.

As this action is more or less complicated, the diagram shown in Figure 4 is provided to show a plurality of successive positions of the type 26 and the positions of the linkages corresponding to said type positions.

The normal position of the movement is shown diagrammatically in solid lines which are given like numerals to those shown in Figures 1, 2, and 3.

When the key 12 is depressed, the lever 32 is moved on its stationary pivot 33 in a counter-clockwise direction and the fulcrum 40 assumes the position shown at 40a. The arm 31 assumes the position shown at 31a; the pivot 39 assumes the position 39a; the arm 18 assumes the position shown at 18a; the pivots 38 and 21 assume the positions shown at 38a and 21a, respectively; and the pivot 37 assumes the position shown at 37a thereby the type is moved to the position 26a. The "a" position is indicated in dotted lines.

During this movement, the type follows a slightly curved path indicated by the numeral 43. The path followed by the pivot 37 is indicated by the numeral 46; the path taken by the pivot 21 is indicated by the numeral 44; the path taken by the pivot 38 is indicated by the numeral 45; and the pivots 39 and 40 each follow circular arcs about the fulcrums 19 and 33 respectively.

As the key is further depressed, the pivot 40 assumes the position shown at 40b and the other levers and pivots assume the "b" positions, shown in dot-dash lines, with the result that the type assumes the position 26b. The path of the type is indicated by the numeral 47; the path taken by the pivot 37 when it moves from the position 37a to 37b is indicated by the numeral 48; the path taken by the pivot 21 is indicated by the numeral 49; and the path taken by the pivot 38 during this movement is designated by the numeral 50.

Pivots 39 and 40 still following circular paths about the fulcrums 19 and 33 respectively, assume the positions 39b and 40b respectively.

As the key is still further depressed, the pivot 40 assumes the position 40c; the pivot 39 assumes the position 39c and the other elements assume the positions indicated by their numerals plus a "c", and shown in heavy dash lines.

When the elements are in this position, it will be noted that the lever 18, shown in the position 18c, has moved to its extreme right position and any further movement of the key will cause this lever to start moving in an opposite direction, or to the left.

The path of the movement of the pivot 37 from the position 37b to the position 37c is indicated by the numeral 51. The path of the movement of the pivot 21 is indicated by the numeral 52; and the path of the pivot 38 is indicated by the numeral 53.

Further depression of the key moves the pivot 40 to the position 40d and the pivot 39 to the position 39d, and moves all of the elements of the action to the positions shown in dash-double dot lines.

It will be noted that the lever 18 has moved from the position 18c to the position 18d in a counterclockwise direction (opposite to its first movement). Due to the reverse movement of the lever 18, the path taken by the pivot 37 in moving from the position 37c to 37d, is more sharply upward than the movement from the b to the c position, indicated by the numeral 51.

Because of the fact that the pivot 37 is moving upwardly and the pivot 21 is moving in a reverse direction, the path taken by the type 26 is beginning to curve downwardly and the face of the type begins its rolling motion which terminates when it contacts the platen 35.

Still further depression of the key moves the pivot 40 from the position 40d to the position 40e thereby bringing the lever 18 still further to the left to the position indicated by the numeral 18e, all of the elements of the action in this position being shown in heavy dotted lines.

The movement to the position 18e brings the pivot 21 from the position 21d to the position 21e. At the same time the pivot 37 is moved from the position 37d still further upward to the position 37e, the combined movement resulting in the moving of the type to the position 26e along the curved line 54 as indicated in Figure 4.

As the key moves still further down, the pivot 40 moves from the position 40e to the position 40f, resulting in the movement of the lever 18 from the position 18e to the position 18f shown in heavy solid lines and bringing the pivot 21 still further to the left to the position 21f, at the same time the lever 28 moves from the position 28e to the position 28f and the pivot 37 carried thereby moves still further upward from the position 37e to the position 37f resulting in the movement of the type 26 to the position indicated by the numeral 26f.

As the key is still further depressed to the end of its stroke, the fulcrum 40 moves from the position 40f to the position 40g and the linkages assume the position shown in heavy dot-dash lines. It will be noted that the pivot 21 moves still further to the left from the position 21f to the position 21g and that the pivot 37 moves from the position 37f still further upward to the position 37g thereby bringing the face of the type 26 to the position 26g in contact with the platen 35.

As the diagram shown in Figure 4 would be more complicated if the rolling action were shown therein, Figure 6 is provided showing the increment of movement of the type in contacting the platen. For example, when the position 26s is reached by the type, the lower corner 55 first makes contact with the platen 35 and the surface of the type is successively brought into contact with the platen until the upper corner 56 comes in contact with the platen. The type is then in the position designated by the numeral 26g.

If the platen 35 were removed, the type would assume the position 26r.

Having explained the diagram, Figure 4, it will be noted that the type 26 moves along the path 43, 47, 54 and that this path, from the position 26c, curves downwardly to a substantial degree.

It will also be noted that the pivot 37 follows a path which bears upwardly and when the

position 37b is reached, its movement is more sharply upward and the successive positions are still more sharply upward. The pivot 21 follows the path 44, 49, 52 along the curved line to the 5 right, after which it reverses, along the same curved line from the position 21c to the position 21g.

The path taken by the pivot 38 moves upwardly to the right assuming the positions 38a 10 and 38b and in successive positions, its movement is more sharply upward to the position 38f and the movement is not so sharply upward in assuming the position 38g from the position 38f. The path of the pivot 39 is through the arc of a 15 circle having the fulcrum 19 as the center and is clockwise until the "c" position is assumed, after which it is counter-clockwise.

The pivot 40, in moving to the position 40a, follows an arc of a circle and the movement of 20 the pivot 37 to the position 37a is almost 5 times as great as the movement of the pivot 40 to the position 40a.

The movement of the pivot 37 from the position 37a to the position 37b, as indicated by the 25 numeral 43, is about three and a half times the movement made by the pivot 40 in moving from the position 40a to the position 40b.

The movement of the pivot 37 from the position 37b to the position 37c, indicated by the 30 numeral 51, is a little over one and a half times the movement made by the pivot 40 from the position 40b to the position 40c.

The movement of the pivot 37 from the position 37c to the position 37d is approximately 35 three fourths of the distance made by the movement of the pivot 40 in going from the position 40c to the position 40d.

It will also be noted that the movement from the position 37d to the position 37e is substantially 40 less than the movement of the pivot 40 from the position 40d to the position 40e.

The movement of the pivot 37 from the position 37e to the position 37f is slightly less than the movement of the pivot 40 from the position 40e to the position 40f; and the movement 45 of the pivot 37 from the position 37f to the position 37g is practically the same as the movement of the pivot 40 from the position 40f to the position 40g.

50 This shortening up of the movement is due to the changes in positions of the linkage and is particularly due to the fact that the lever 18 moves retrograde during the last portion of the stroke.

55 As the path of movement of the pivot 37 shortens, the power of the key over the type 26g through the medium of the linkage increases, so that when the face of the type reaches the platen, the last part of pressure applied to the 60 key is applied to the type through this powerful linkage, thereby enabling the production of more perfect copies than has heretofore been possible to obtain from a noiseless typewriter.

In the embodiment herein shown and described, all of the angles formed in the various members of the action are preferably laid out on an angle of 45° or a multiple thereof but it is distinctly understood that these angles may be changed without departing from the spirit of the 70 invention.

While the type 27 is shown out of line with the center line of the platen it is obvious that it can be brought into line with the platen by shifting the platen downwardly, or by moving the 75 member supporting the fixed fulcrums 11, 19 and

33 upwardly. Either option may be accomplished with a shift key in the usual manner. As such movements are well known in the art they need not here be described in detail.

The energy applied to the key is delivered to 5 the type 26 through two separate paths. In this specification, one of the paths will be termed an "ordinary path" and the other an "extraordinary path".

Referring to Figures 1, 2, and 3, the energy 10 through the "ordinary path" is delivered to the fulcrum 37 via the arm 29 and the arm 28. Energy through the "extraordinary path" is delivered to the type carrier via the lever 18 and the fulcrum 21. 15

During the first part of the stroke and up to the position 26b of the type, the energy is delivered to the type carrier 26 only through the "ordinary path". From this position on to the printing position, the energy is delivered to the 20 type carrier 26 via both the ordinary and the extraordinary paths.

During the latter portion of the stroke, the pivotal movement of the type carrier 26 is about 25 a constantly changing point between the pivot 21 and the pivot 37. This pivotal movement, as the type approaches the platen, brings the type more nearly in line with the surface of the platen and causes the lower end of the face of the type to come in contact with the platen first and as 30 the movement further progresses, the surface of the face of the type is successively brought into contact with the platen until the entire face of the type is in contact with the platen.

In the modification shown in Figure 7, a type 35 carrier 57 has secured thereto a type member 58 and is connected by means of a pivot joint 59 to one end of a straight lever 60. The other end of the lever 60 is connected by means of a pivot joint 61 to one arm 62 of a bell crank 63. The 40 other arm 64 of the bell crank is connected by means of a pivot joint 65 to a lever 66. 45

The bell crank 63 is connected by means of a pivot joint 67 to a lever 68. The other end of the lever 66 is connected by means of a pivot 50 joint 69 to a lever 70 and a lever 71. The lever 70 is mounted on a fixed fulcrum 72 and has its other end connected to a pull bar 73 by means of a pivot joint 74. The other end of the pull bar 73 is connected to the key lever 75 by means 55 of a pivot joint 76. One end of the key lever is mounted on a fixed fulcrum 77 and the other end is provided with a key 78.

The lever 68 is connected to a lever 79 by means of a pivot 80 and is connected to the lever 55 71 by means of a pivot 81. The end of the lever 68 is mounted on a fulcrum 82. An arm 83 has one end connected to the lever 79 by means of a pivot joint 84 and the other end connected to the lever 71 by means of a pivot joint 85. The 60 upper end of the lever 79 is connected to the lower end of the type 57 by means of a pivot joint 86.

When the key 78 is depressed and moved to the position 78a the linkages and pivots assume 65 the positions shown in light dot-dash lines. This brings the type 58 from its elevated position to a position near the platen indicated by the numeral 58a.

As the key 78 is further depressed to the position 78b the pivots and linkages assume the positions shown in heavy dotted lines and the type is shown in the printing position and in contact with the platen 87, and indicated by the numeral 75 58b.

It will be noted that the short movement of the key from the position 78 to the position 78a moves the type 58 through a substantial distance which is approximately more than ten times the movement of the key. The type in moving from the position 58a to the position 58b only moves about three times as far as the key does in moving from the position 78a to the position 78b.

The lever 68 moves clockwise until it reaches the position 68a and from then on it reverses its direction of movement and comes to rest at the position 68b when the type 58 contacts the platen.

Although this movement is similar in some respects to the movement shown in Figures 1, 2, and 3, it is comprised of more parts and is therefore more expensive to manufacture and consequently the movement shown in Figures 1, 2, and 3 is believed to be preferable.

This latter movement is of such form that it can be mounted in frames of existing typewriters of the universal bar type now in wide use.

It has distinct advantages in that the work is always visible; there is plenty of room for erasures and corrections; the action is substantially noiseless and, although it is noiseless, many more legible copies can be made due to the power applied to the type during the last stage of its motion, through the medium of the powerful linkages.

Because of the small number of parts and due to the fact that all of the fulcrums and pivot joints are made with "working fits" instead of "sloppy fits" as has been the practice heretofore in noiseless typewriters, there is no lost motion in these joints therefore perfect alignment, both horizontally and vertically, is obtained and the consequent perfect or beautiful printing is effected due to the rolling action of the type when it comes immediately adjacent to the platen.

Although two simple embodiments of the invention are herein shown and described, it is obvious that many changes may be made by those skilled in the art without departing from the spirit of the invention as defined in the accompanying claims.

What is claimed is:

1. In a typewriter having a platen and a plurality of type carrying members, the method of 50 reducing the noise of the contact of the type with the platen, which consists in applying force in the same direction to one of said members by means of two mediums, thereby tending to move the member along a path extending from a position of rest to said platen; and while said member is in motion, changing the direction in which said force is applied by one of said mediums, thereby progressively distorting said path as the type approaches the platen.

60 2. The method according to claim 1 in which said member is moved to a position near the platen before force applied thereto through said last medium is changed in direction.

3. The method according to claim 1 in which 65 the face of the type is brought into contact with the platen progressively.

4. In combination, a platen, a type carrier bearing a type element, a key, a key lever supporting said key, linkage between said key lever and said 70 type carrier for moving the latter from its normal position toward said platen, and a pivoted member interconnected with said linkage and said type carrier, and adapted to impart a pivotal movement of changing radii to said type carrier 75 and a resultant rolling movement to said type as

it approaches and comes into contact with the platen.

5. In a device of the character described, a support, a platen, a carrier bearing a type element, a key, a key lever supporting said key, a lever fulcrumed on said support, a pivot connecting one end of said carrier to said lever, a bell crank fulcrumed on said lever, a link connecting one arm of said bell crank with said carrier, a second lever fulcrumed on said support 10 and having one end pivotally connected to the other arm of the bell crank, and a pull bar connecting said second lever to said key lever.

6. In a device of the character described, a support, a platen, a carrier bearing a type member, 15 a key, a key lever supporting said key, a lever fulcrumed on said support, a pivot connecting one end of said carrier to said lever, a second lever having one end pivotally connected to said carrier, and means connecting said levers to said key lever, said means including a third lever fulcrumed on said support and adapted to swing said first lever on its fulcrum in fixed relation to said second lever for a portion of a key stroke, 20 and adapted to swing said first lever on its fulcrum in an opposite direction and in changing relation to said second lever during the remainder of said key stroke.

7. In a device of the character described, a support, a platen, a carrier bearing a type member, a key, a key lever supporting said key, a lever fulcrumed on said support, a pivot connecting one end of said carrier to said lever, a second lever having one end pivotally connected to said carrier, and means connecting said levers to said key lever, said means including a third lever fulcrumed on said support and connected by means of a pull bar to said key lever and adapted, when the key lever is depressed, to swing said first lever on its fulcrum in fixed relation to said second lever for a portion of the key stroke, 35 and adapted to swing said first lever on its fulcrum in an opposite direction and in changing relation to said second lever the remainder of said stroke.

8. In a device of the character described, a support, a platen, a carrier bearing a type member, a key, a key lever supporting said key, a lever fulcrumed on said support, a pivot connecting one end of said carrier to said lever, a second lever having one end pivotally connected to said carrier, a third lever fulcrumed on said support, a pull bar linking said third lever to said key lever, and means between said third lever and said first and second levers for moving said carrier from a 50 normal position toward said platen, maintaining said first and second levers in fixed relation during a portion of the movement and varying the relation between said first and second levers for the remainder of the movement.

9. In a device of the character described, a support, a platen, a carrier bearing a type element, a key, a key lever supporting said key, a lever fulcrumed on said support, a pivot connecting said carrier to said lever, a bell crank pivotally supported on said lever, a link connecting said bell crank to said carrier, a second lever fulcrumed on said support and having one end pivotally connected to said bell crank, and a pull bar connecting said second lever to said key lever, the pivotal support of said bell crank being adapted 55 to act as a fulcrum during a portion of a key stroke and as a pivot during the remainder of the key stroke.

10. In a device of the character described, a support, a platen, a carrier bearing a type ele- 70

75

ment, a key, a key lever supporting said key, a lever fulcrumed on said support, a pivot connecting one end of said carrier to one end of said lever thereby making the latter a support for 5 said carrier, a bell crank fulcrumed on said lever, a link member connecting one arm of said bell crank with said carrier, a second lever fulcrumed on said support, having one end pivotally connected to the other arm of the bell crank and 10 normally at rest in angular relation to said other arm of the bell crank, and means for moving said last lever about its fulcrum to propel said carrier toward said platen thereby bringing the same straight in line with said other arm of the bell 15 crank to position said carrier adjacent to said platen and thereafter bringing said latter lever and said other arm into angular relation opposite in phase to said normal position to complete the movement of said carrier thereby bringing 20 the type member thereon into printing contact with said platen.

11. In a device of the character described, a support, a platen, a carrier bearing a type element, a key, a key lever supporting said key, 25 a lever fulcrumed on said support, a pivot connecting one end of said carrier to one end of said lever, a bell crank fulcrumed on said lever adjacent to the fulcrum of said lever, a link having one end pivotally connected to one arm of the 30 bell crank and having its other end pivotally connected to said carrier at a point between the ends thereof, a second lever fulcrumed on said support and having one end thereof pivotally connected to the second arm of said bell crank, 35 and means connecting said second lever to said key lever, said first lever serving as a support for said carrier said bell crank and said link, and

adapted during a portion of a key stroke, to move in one direction, and to move in an opposite direction during the remainder of the key stroke thereby causing the type member on said carrier to follow a path becoming increasingly curvilinear 5 in character and of shortening radius as it approaches and contacts the platen.

12. A typewriter movement including a type carrier having an angular arm extending therefrom, a lever, a fulcrum supporting said lever, 10 a pivot connecting the end of said arm with one end of said lever, a bell crank fulcrumed on said lever, a link having one end pivotally connected to one arm of said bell crank and the other end pivotally connected to the arm of said type carrier 15 at a point spaced apart from said first pivot, said lever, said arms and said link normally forming an irregular quadrangular figure, and means connected to the other arm of said bell crank for moving said type member along a path, said 20 means adapted to move said lever in one direction during a portion of said movement and to move said lever in an opposite direction during the remainder of the movement, said lever, the arm of said carrier, said first arm of the bell 25 crank and said link being maintained in fixed relation during the first portion of said movement and being progressively varied in relation during the remainder of the movement.

13. The invention according to claim 12 in 30 which a platen is provided; in which a frame is provided for supporting said fulcrum and said platen; and in which said means includes a key lever fulcrumed on said frame, whereby said type member is given a rolling movement as it approaches and contacts the platen.

SEYED KHALIL.
